UNITED STATES PATENT OFFICE.

BERNARD H. DAVIS, OF FULLERTON, CALIFORNIA.

PITMAN END.

Application filed March 18, 1925. Serial No. 16,327.

This invention relates to oil well rigs and is particularly directed to an improvement in the pitman end which co-operates with the wrist pin of a band wheel crank.

At present the conventional pitman which links the walking beam with the band wheel crank is merely provided with a socket for the reception of the wrist pin, and as the pitman is generally made of wood the bearing hole rapidly wears large and there is no effective way of reducing the size of the hole, or in other words of tightening the bearing.

An object of the invention is to provide an improved pitman end, preferably made of metal wherein an adjustable bearing is adapted to co-operate with the wrist pin of the band wheel crank.

A further object is to incorporate in a pitman end of the type described, demountable parts so that when the bearing parts or other parts which wear may be readily replaced.

A further object is to provide means for rapidly coupling the pitman end bearing with a wrist pin or quickly disengaging the bearing if desired.

Other objects and advantages will be made manifest in the following specification of an embodiment of the invention illustrated in the accompanying drawings, in which:

Figure 1 is a vertical side view partly in section of the pitman end.

Figure 2 is a vertical end view of the pitman end.

Figure 3 is a fragmentary sectional view of the pitman end taken on the line 3—3 of Figure 1.

Figure 4 is a fragmentary side view of a standard oil rig having the improved pitman end incorporated therewith.

The details of construction are as follows:

Referring to Figure 4, a walking beam 2 swinging upon a Sampson post 3 is linked with a band wheel 4 by a pitman rod 5 which engages a wrist pin 6 at the end of a band wheel crank 7.

The lower end of the pitman is provided with a bearing 8 which is formed in two halves, a lower half 9 and an upper half 10. The bearing is adapted to be retained in a box 11 provided in a counterbalance 12 which may be a suitable casting and is preferably rounded at its lower end, the

upper ends 13 and 14 of the counterbalance 55 being substantially horizontal at each side of the box 11.

The upper half 10 of the bearing is formed with a block 15 which extends crosswise of the counterbalance as indicated in Figure 1 and has an inclined upper face 16. Adapted to slidably engage the upper face 16 of the block 15 is a wedge member 17 whose lower face is inclined to co-operate with the inclined face 16, and whose upper face 18 is substantially horizontal. A guide block 19 having a horizontal lower face adapted to engage the upper face of the wedge member 17 has a roughly U shaped outline and is adapted to seat upon the lower end 20 of the upper part of the pitman, which may be 60 of wood or any suitable material.

The guide block 19, the wedge member 17, and the block 15 are all dove-tailed longitudinally of their extension and crosswise of the counterbalance, so that they may be 65 slidably related one to the other and for other purposes hereinafter described.

A metal band 21 extends from the upper end of the pitman 5 down what has been referred to as a vertical end of a pitman, is looped around the lower end of the counterbalance 12 and passes upwardly to the upper end of the pitman. This band 21 is intended to firmly secure the counterbalance 80 and the bearing mechanism in secure relationship with the upper part of the pitman. Bolts 22 extend through the metal band and through the guide block 19 rigidly maintaining the guide block at the lower end of the upper part 20 of the pitman.

The wedge member 17 is provided with a longitudinal and horizontally threaded opening 25 and a recess 26 at the larger end of the wedge member and co-extensive with the threaded opening 25. A jack screw 27 is adapted to operate in the threaded opening 25 and is provided with a crank 28 which may be removed when the pitman is operating. The jack screw extends through an opening in the metal band 21 and is provided immediately adjacent the inner side of the band with an annular shoulder 29 adapted to act as a thrust bearing, and upon the outer side of the metal band a ratchet wheel 30 which is adapted to act as a second thrust bearing for the jack screw and is further adapted to be engaged by a dog 31.

which is pivoted upon the metal band immediately above the ratchet wheel.

The lower half 9 of the bearing is adapted to seat loosely in the box 11 until pressure is brought to bear upon the bearing and the height of the bearing may be adjusted by placing shims between the bottom of the box and the bottom of the bearing block.

In the operation of the invention the upper half 10 of the bearing should be separated from the lower half 9 by turning the crank 28 in a left hand direction, which will cause the wedge member 17 to be drawn outwardly, inasmuch as the annular shoulder 29 and ratchet wheel 30 provide thrust bearings restricting the shaft from longitudinal movement, and the recess 26 will accommodate the annular shoulder 29. Inasmuch as the guide block 19 is rigid with the pitman and the wedge member 17 is slidably dove-tailed with the guide member and also with the inclined face of the block 15, the outward movement of the wedge member 17 will cause the block 15 to be raised and consequently the upper half 10 of the bearing will be raised considerably above its normal position. The bearing may then be drawn into approximate engagement with the wrist pin 6 on the band wheel crank and a turning of the crank 28 in a right hand direction will cause the wedge member 17 to slide inwardly co-acting with the block 19 to press the block 15 downwardly so that the bearing may be tightened as desired. The dog 31 dragging on the ratchet wheel 30 will prevent retraction of the wedge member so that the bearing may be firmly retained at the adjustment desired. The crank 28 should then be removed while the pitman operates.

It will be noted that on account of the dove-tail connection of the wedge member 17 to the block 15 and the guide block 19 that when this wedge member is drawn outwardly the bearing block 15 may be positively drawn away from the wrist pin and may be held in such position by means of the ratchet and pawl.

Various changes may be made without departing from the spirit of the invention as claimed. What is claimed is:

1. In a pitman rod, a pitman end having

a split bearing, one half of the bearing being stationary with respect to the pitman rod and the other half being movable relatively thereto, a guide block mounted upon the pitman rod, a wedge disposed between the movable half of the bearing and the guide block, said wedge having a dove-tailed connection with the guide block and the movable half of the bearing, whereby it may slide relatively thereto but can not be separated therefrom, a screw threaded into the wedge and held against endwise movement relatively to the pitman rod, a ratchet wheel rigidly mounted upon the screw, and a pawl mounted upon the pitman rod engageable upon the ratchet wheel, whereby the screw may be rotated in either direction to cause the wedge to slide in either direction and thus move the movable half of the bearing in either direction.

2. In a pitman rod, a metal band encircling the lower end of the pitman rod, a box mounted within said band and fastened thereby to the pitman rod, a bearing in said box, said bearing comprising a lower half adapted to fit in the box, an upper half adapted to cooperate with the lower half and having an inclined face, a guide block disposed above said box, and a wedge member adapted to slidably engage the guide block and the inclined face of the upper half of the bearing, the wedge member, the upper half of the bearing and the guide block having a dove-tailed connection, a screw threaded into the wedge member having one end rotatably mounted in said band, said screw being held against endwise movement through the band, a ratchet wheel rigidly mounted upon the screw against the outer side of the band, and a pawl mounted upon the band engageable upon the ratchet wheel, said screw having a non-circular end whereby a crank or the like may be detachably applied thereto to rotate the screw in either direction and cause the movable half of the bearing to move toward or away from the stationary half of the bearing.

In testimony whereof I have signed my name to this specification.

BERNARD H. DAVIS.
